UNITED STATES PATENT OFFICE

ANDREW MAIN, OF CLEVELAND, OHIO, ASSIGNOR, BY MESNE ASSIGNMENTS, TO CLEVELAND FARE BOX AND FOUR-WAY LOCK CO., OF CLEVELAND, OHIO, A CORPORATION OF OHIO

JAIL LOCK

Application filed May 11, 1931. Serial No. 536,401.

My invention relates to lock mechanisms of the rotary plug and cylinder type. One object of the invention is to provide such a lock adapted for actuating a sliding bolt and so arranged that the plug and cylinder as an entity, may be removed from the front face or wall of the lock mechanism without access to any other face thereof and by an operation relatively difficult to an unauthorized

person but capable of being readily performed by an authorized person with proper tools or equipment. Another object is generally to improve the plug and cylinder mechanism in a manner to simplify the same and also to take the key drive away from the key ward for protecting such wards.

Further objects of the invention are in part obvious and in part will appear more in detail hereinafter.

In the drawings, Fig. 1 is a plan view showing the front face of the lock mechanism; Fig. 2 is a plan view of the lock mechanism shown in Fig. 1 with the cover and parts attached thereto removed showing the locking bolt; Fig. 3 is a view of the key for operating the lock mechanism; Fig. 4 is a sectional view taken on the line 4-4 of Fig. 1; Fig. 5 is a sectional view taken on the line 5-5 of Fig. 1; Fig. 6 is a sectional view taken on the line 6-6 of Fig. 4; and Fig. 7 is a view, partly in section, taken on the line 7-7 of Fig. 4.

The lock shown in the drawings is designed particularly for use in prisons, such as on individual confining cells and corridor doors, although it is not limited thereto. As shown, the lock consists of a base plate or casting 1 providing a means for securing the lock to a suitable support. For instance, the base plate or casting may be welded permanently along its edges to a metal plate of a wall or door. Such plate carries the operating parts of the lock mechanism, which mechanism is covered by a casing 2 attached to the plate 1 and includes a sliding bolt 3 having its locking portion guided in an opening in the wall of the casing 2, the bolt also having an elongated guiding slot or opening 4 through which extend plug operated rotatable lock parts comprising a lever arm connector or

roll back 5 having a portion thereof of sleeve form journaled on an annular boss 6 rigidly mounted on the plate 1. The roll back also is provided with an upper cylindrical recess 7 into which extends the inner end of a rotary plug 8 provided with a non-circular driving projection 9 entering a corresponding socket 10 in the roll back 5 for operating the same.

The roll back 5 includes the arm 11 which serves as a bolt throwing member by cooperating with one or the other of two throwing abutments 12, the outermost end of the arm 11 and the throwing abutments 12 being cam-shaped whereby arcuate movement of the arm 11 will cause longitudinal movement of the bolt 3, and being so shaped that when in one or the other of its thrown positions the bolt 3 is locked against longitudinal movement except by rotation of the plug 8, roll back 5, and arcuate swinging of the arm 11. That is, the bolt can not be moved longitudinally by pressure or pull on the end thereof. Thus, a locking means is provided to prevent bolt movement except by rotation of the plug 8. In throwing the bolt 3 to locked position, the arm 11 is turned counter-clockwise 90° in Fig. 2, first engaging one of the abutments 12 and then camming the bolt to locked position, this movement continuing until a portion of the cam surface of the arm 11 that has the same curvature as the curvature of the throwing abutments 12 is concentric therewith whereupon the bolt will be locked in its outwardly thrown position. Reverse bolt movement and locking of the bolt against longitudinal movement are accomplished by the same amount (90°) of arm movement in the reverse direction.

The casing or cover 2 includes an annular boss 13 presenting a sleeve portion in the socket or recess of which a cylinder or barrel 14 is mounted, having an annular flange 15 resting on a shoulder 16 in the sleeve. Such annular flange fits loosely within the sleeve but is provided with openings 17 adapted to fit over pins 18 extending upwardly from the shoulder whereby the cylinder or barrel 14 is held against rotation. Plug 8 fits loosely within the cylinder or barrel 14.

and is rotatable relative thereto, being held within it by means of an annular plate 19 that is held on the annular flange of the cylinder or barrel by means of screws 20, 5 the plate fitting over the plug 8 and abutting against an annular shoulder 21 thereon. The provision of the annular plate 19 as a means for holding the plug 8 within the cylinder or barrel 14, permits the cylinder 10 and plug to be handled as a unit without fear of disassembly thereof. This has the advantage of making it possible for the cylinder and plug members to be assembled as a unit at the factory and then shipped to the 15 point of use to be substituted for other units that have been removed from lock casings previously in use on a door. That is, in the event that a prisoner renders a lock useless by jamming or otherwise injuring the lock 20 mechanism by driving something into the key opening of the plug, the cylinder and plug can be removed from the lock as a unit, a new unit substituted therefor, and the injured unit returned to the place of manufacture 25 for repair or renewal. The advantages of this feature will be obvious.

Suitable means are provided for confining the plug in the socket or recess. As shown, the cylinder or barrel 14 and plug 8 are confined in the socket or recess formed in the 30 boss 13 by a washer 22 threaded into the outer end of the sleeve and dowelled into the cylinder or barrel by means of pins 24 extending through openings in the washer 35 and corresponding openings 25 in the cylinder or barrel. The outermost ends of the pins 24 may be ground off flush with the outer face of the washer after the parts are assembled, which prevents removal of the 40 washer and other parts of the lock, except by an authorized person with proper equipment. Also, the diameter of the opening in washer 22 is such that independently of the plate 19 said washer also locks or confines 45 the plug to its seat in the cylinder and casing.

Plug 8 is provided with a cruciform key-way or slot 26 for a key 27 having a ward portion of like cross section and whose wards 50 28 actuate tumbler levers 29 cooperating with longitudinal grooves 30 in the cylinder or barrel 14. This construction is substantially similar to that shown and described in my prior application for Cylinder lock filed 55 October 7, 1929, Serial No. 400,270 to which reference may be had for details not here described. As in this prior construction, the plug is made in two parts, a body 31 and a cap 32, the body being of cylindrical form 60 carrying the integral driver 9 at one end and its tumbler slots being formed by two transverse diametrical saw slots extending from its outer end towards the driver 9 at its inner end to form four quadrant-shaped 65 segments integrally connected at only one

end. Cap 32 is preferably countersunk and sleeved over the reduced end portions of such segments with a driving fit and is preferably secured in any suitable manner to each one thereof as, for instance, by the countersunk set screw 33. The cap is also provided with a non-circular socket 34 to receive a like-shaped portion 35 of the key when the latter is fully inserted into the keyway in the plug. 75

With this arrangement, when the key is pushed fully home, the tumblers are entirely withdrawn from the cylinder slots into the plug, which is therefore free to rotate in its cylinder. Also, the driving part 35 of 80 the key shank is non-circular as hereinbefore stated and includes one rounded side 36 which cooperates with a rounded side 37 of the cap to prevent the key from being inserted in any but one position, as in the 85 socket 34. As a result, the proper wards on the key holes unavoidably register with the proper grooves of the cruciform key slot of the plug. Such construction of the lock and key insures equal distribution of turning movement to all parts of the plug and prevents any possibility of bending or flexing of an individual segment or part which might bind or otherwise interfere with the 90 action of the tumbler levers. 95

Referring to the above, I have provided a lock that is usually applied to that side of a door which is out of reach of a prisoner to prevent his tampering with the lock, and which embodies numerous novel and advantageous features. The lock has been so constructed that the cylinder or barrel and plug as a unit may be removed from the lock casing with comparative ease providing the proper tools are had. This is due to the 100 fact that the cylinder or barrel and plug have a substantially loose fit within the lock casing, being held against rotation therein by use of two pins and being held against endwise removal therefrom by the use of a 105 washer that is dowelled or otherwise secured in the casing and to the cylinder or barrel. Thus, a lock has been provided that may be 110 easily repaired or replaced without undue time or expense. 115

What I claim is:

1. Lock mechanism, comprising a hollow casing having an opening, a movable bolt therein, a roll-back having a non-circular driving portion opposite the opening of the 120 casing and adapted to move said bolt, and a lock unit insertable by straight line movement through said opening into said casing and including cylinder and plug members, the latter having a non-circular driving portion 125 corresponding to and adapted to cooperate with the non-circular driving portion of the roll-back, connecting means between said cylinder and plug members permitting relative rotation but preventing relative lon- 130

gitudinal movement therebetween, whereby said members may be assembled and handled as a unit and so introduced into or removed from the casing, interlocking means between 5 said unit and the casing to prevent rotation of the cylinder therein, a washer threaded into the casing for confining said unit therein, and means for locking the washer to the casing against unauthorized removal, said last 10 named means including pin means extending through said washer and parts of said cylinder.

2. Lock mechanism, comprising a hollow casing having an opening, a movable bolt 15 therein, a roll-back having a non-circular driving portion opposite the opening in the casing and adapted to move said bolt, and a lock unit insertable by straight line movement through said opening into said casing

20

and including cylinder and plug members, the latter having a non-circular driving portion corresponding to and adapted to cooperate with that of the roll-back, connecting means between said cylinder and plug 70 members permitting relative rotation but preventing relative longitudinal movement therebetween, whereby said members may be assembled and handled as a unit and introduced into or removed from said casing, 75 interlocking means including dowel pins connecting said casing to said unit to prevent rotation of the cylinder in the casing, and means for locking said unit in the casing to prevent unauthorized removal thereof.

In testimony whereof I hereby affix my signature.

ANDREW MAIN.
